UNITED STATES PATENT OFFICE

STEPHEN JOHN NOLAN, OF MOUNT VERNON, NEW YORK

WEATHER STRIP FOR WINDOWS OR DOORS

Application filed June 11, 1931. Serial No. 543,696.

This invention relates to new and useful improvements in weather strips for doors, windows and the like.

It is one of the objects of the present invention to provide a weather strip which will at all times form a weather tight joint between a window and its frame or a door and its frame or between any two parts in connection with which the weather strip is employed.

10 It is a further object of the invention so to construct a device of this character that the weather strip contacts with the parts with which it engages under pressure, thus insuring a tight joint between the weather strip and that member which it engages.

15 It is a still further object of the invention so to construct a weather strip of the above mentioned character that it may be securely retained in position without the use of separate fastening means such as screws, bolts or the like.

20 It is a further object of the invention so to construct a weather strip of the aforementioned character that it may be attached to windows of various sizes within certain limits without necessitating special fitting thereof.

25 With the above and other objects in view, reference will be had to the accompanying drawing in which;

30 Figure 1 is a fragmentary perspective view of a window of the casement type showing a weather strip constructed in accordance with the present invention attached thereto,

35 Figure 2 is a detail sectional view taken on the line 2—2 of Figure 1,

40 Figure 3 is a detail sectional view showing a slightly modified form of the invention and illustrating the weather strip carried by the window sash frame instead of the window frame, and;

45 Figure 4 is a detail view in section of the weather strip.

Referring more specifically to the drawing, the reference character A designates a window frame, and B designates the window sash frame, the window in this particular embodiment of the invention being of the casement type.

The frame A consists of a web portion 10 having oppositely extended flanges 11 and 12

the flange 11 projecting downwardly around a shoulder 13 of the sill and the flange 12 projecting upwardly as best illustrated in Figures 1 and 3. The sash frame B comprises a web portion 15 having a depending 55 flange 16 and an upstanding flange 17 the latter receiving the window pane 18 with a suitable sealing medium such as 19 interposed therebetween.

The weather strip consists of a channel 60 member C having a bottom wall 20 and two side flanges 21 and 22. Formed integral with the side flange 21, there is a resilient member 23 which extends inwardly of the channel and has its inner edge rolled to form a 65 bead 24. This bead 24 is adapted under certain operating conditions to be received within a channel 25 formed in the inner base of the wall 21 of the channel member C as will be hereinafter described.

70 Projecting from the wall 22 of the channel member C and preferably formed integral therewith, there is a resilient member 26 and upon the free end of this resilient member 26, there is a channel member 27 composed 75 of a bottom wall 28 and side walls 29 and 30. Mounted in this channel member 28 there is a weather strip 32 which may be of felt or other suitable material and which is retained in position against accidental displacement by a flange or the like 33 formed on the extremity of the wall 29 of the channel member 27.

75 When the device is employed as illustrated in Figures 1 and 2 of the drawing, the channel member C is adapted to receive the upstanding flange 12 of the window frame. When it is inserted over the upstanding flange 12 of the window frame A, the resilient member 23 is placed under tension and its 80 bead 24 occupies a position in the channel or recess 25 in the wall 21 of the channel C. The resiliency of this member serves to maintain the device in position upon the window frame. In this form of the invention the 85 window when moved to its closed position, engages the weather strip 32 and flexes the member 26 placing it under tension and thus insuring that the weather strip at all times engages all portions of the window frame 100.

when the window sash is in closed position thus insuring a weather tight joint between the several parts.

In that form of the invention illustrated in Figure 3, the weather strip is attached to the window sash and its operation is substantially the same in that as the sash is moved to closed position the weather strip will engage the depending flange 11 of the window frame and form a tight joint therewith the member 10 26 being placed under tension.

Corner pieces 40 are employed for the purpose of providing a finish to the window, and to cover up irregularities in the bend or joints between the side and end members. 15 The corner pieces are of substantially right angular form, and consist of channel members adapted to receive in their legs the channel members C heretofore mentioned.

When the invention has been herein illustrated in a preferred form, it is to be understood that the invention is not to be limited to the specific construction herein shown and that it may be practiced in other forms without departing from the spirit thereof.

Having thus described the invention, what is claimed as new, and what it is desired to secure by Letters Patent of the United States, is;

30 1. A weather strip for window and door openings comprising a resilient channel shaped clip member adapted to removably engage a portion of a door or window construction, a resilient portion formed integral with one of the side walls of said clip member, said resilient portion being arranged exteriorly of the clip member and normally spaced therefrom to permit movement of the resilient portion relative to the clip member, 40 and a sealing member carried by said resilient portion.

2. A weather strip for windows or doors comprising a channel shaped resilient member adapted to embrace the member to which the weather strip is to be attached, a reinforced resilient means carried by one of the walls of said channel shaped member and projecting into the channel, said channel being adapted to receive said reinforced resilient member, an adjustable resilient member carried by the other wall of said channel shaped member, means formed on said adjustable resilient member for carrying a weather strip, and a weather strip mounted in 55 said means.

In testimony whereof I affix my signature.
STEPHEN JOHN NOLAN.
